UNITED STATES PATENT OFFICE.

THADDEUS F. TYLER, OF HAVERHILL, MASSACHUSETTS.

WOOD-HEEL CLAMP.

Application filed June 14, 1923. Serial No. 645,309.

To all whom it may concern:

Be it known that I, THADDEUS FRANK TYLER, a citizen of the United States, and resident of Haverhill, in the county of Essex and State of Massachusetts, have invented 5 an Improvement in Wood-Heel Clamps, of which the following is a specification.

In the process of manufacturing wood heels, the sides and back of the heels are 10 covered with leather or cloth, adhesively connected thereto, and, in performing this operation the heel is usually held in a clamp or jack with the tread face up. In the clamps which have been employed for this 15 purpose, the top engaging member has usually consisted of an arm adjustably mounted on a fixed vertical post, said arm having at its end a quick acting cam which is arranged to be operated by a handle connected thereto, and to force the upper 20 clamping member into engagement with the heel. With this form of device it is necessary to have the relative adjustment of the base-supporting means and the arm correspond quite accurately to the height of the 25 heel, as the motion secured by the cam is very short. As the time required to place the heel in position and to remove it is a factor of considerable importance, where 30 large numbers of heels are to be covered, the time lost in making adjustments and in operating the cam lever become matters of considerable importance.

The chief objection, however, to the construction which has generally been used for 35 this purpose is that the arm and cam-operated clamping means for engaging the top of the heel are so supported that the view which the operator has of the surfaces to be covered is seriously obstructed, and it is very desirable, in order that the work may 40 be readily and properly done, for the operator to be able to see without difficulty all portions of the surfaces to be covered. It 45 is also desirable that the clamp for holding the heel be so constructed that the manipulation of the covering, in placing it in position, smoothing out all wrinkles, and drawing it tightly over the surfaces to which it 50 is connected, shall be interfered with as little as possible.

The objects of my invention are to provide a form of clamp for the purpose above indicated, which may be opened and closed 55 by means of a treadle, so that the operator will have both hands free for removing one

heel and placing another in position, and further to provide a clamp, which is so constructed that the view which the operator has of the work will be practically unobstructed, and the work may be rapidly and satisfactorily performed.

I accomplish these objects by the means hereinafter described and illustrated in the accompanying drawing, in which:

Fig. 1 is a central vertical sectional view of a form of heel clamp containing an embodiment of my invention, and

Fig. 2 is a plan view thereof.

As shown in the drawing, the clamp is 70 adapted to be mounted upon a bench 1, in which a post 2 is mounted, said post having a threaded bore extending from its upper end, in which a stem 3 is threaded, said stem having a pair of ears 4 at its upper end, 75 between which a flange 5, on the under side of the base engaged member 6, is arranged to tilt on a pivot 7. The lower edge portion of the flange 5 is provided with a series of corrugations or notches 8, which are 80 adapted to be engaged by a spring pressed bolt 9 mounted in the stem 3, said bolt having a handle 10 for depressing the same, so that the inclination of the base engaging member 6 may be varied according to the 85 pitch of the heel, and the top may be adjusted to a horizontal position. A lock nut 11 is provided on the stem 3 so that the stem may be securely locked in any position to which it may be adjusted. A tubular casing 90 12 is fixed in the bench 1, and a rod 13 is slidably mounted therein, said rod being extended entirely therethrough, and through the opening in the bench, and being guided therein by a cap 18 on the upper end, and 95 a plug 26 in the lower end of said casing. The lower end of said rod 13 is loosely connected to a lever 14 pivoted on a bracket 15 on the under side of the bench, the opposite end of the lever 14 being connected by 100 a link 16 to a treadle 17 so that, when the treadle is depressed, the rod 13 may be lifted. A coiled spring 19 is arranged in the casing 12 about the rod 13 between the cap 18 and a pin 20 fixed in the rod 13, so 105 that said spring will normally act to press the rod 13 downwardly. The upper end portion of the rod 13 is provided with an internally screw threaded bore to receive one end of an arm 21, which is screwed therein, 110 said arm being adapted to be locked in any position to which it may be adjusted by a

lock nut 22 threaded thereon and adapted to be screwed against the end of the rod. Said arm 21 consists of a rigid metal rod of relatively small diameter, bent at right angles at two points to form a horizontal portion 23 and a depending, heel-top-engaging portion 24, the extreme end of which is provided with a downwardly facing corrugated face 25.

- 10 With the above described construction, when the treadle is depressed, the arm 21 will be raised as indicated in the dotted line position of Fig. 1, in which position the heel may be readily placed in position on 15 the base member 6, or removed therefrom. When the heel has been placed in position, the pressure on the treadle will be removed, permitting the spring 19 to force the arm downwardly and clamp the heel 20 firmly onto the base 6, so that the heel may be clamped almost instantly without using the hands. As the arm 21 is of small diameter, it will not obstruct the view of the operator to an objectionable extent, so that 25 after the heel has been clamped in position the covering may be applied in the correct position and drawn tightly over the surface of the heel, so that all wrinkles will be removed. This work may be rapidly performed, as the work of the hands of the operator as well as the vision will be practically unobstructed. The range of move-

ment provided by the treadle is such that heels which vary considerably in height 35 may be clamped in position without readjustment of the parts, but in case adjustment is necessary for wider variations, the arm 21 may be adjusted in the rod 13, by screwing it up or down therein, or the height of 40 the base support may be adjusted, as previously described. When the heel is removed and pressure on the treadle is removed, the pin 20 will rest on the plug 26, which will serve as a stop.

45 I claim—

A heel clamp comprising a fixed member having an upwardly facing heel-supporting face, a vertically disposed casing mounted adjacent said member, a rod extending through said casing and reciprocally mounted therein, a spring engaged with said casing and rod to press the rod downward, a treadle for lifting said rod, and a rigid arm connected to the upper end of 50 said rod and arranged for adjustment longitudinally thereof, said arm being extended horizontally and having a depending end portion provided with a heel top engaging 55 face at its lower end arranged in cooperative relation with said supporting face.

60 In testimony whereof I have signed my name to this specification.

THADDEUS F. TYLER.
